UNITED STATES PATENT OFFICE.

PAUL W. LEFFLER, OF CHICAGO, ILLINOIS; ANNA A. LEFFLER, ADMINISTRATRIX OF SAID PAUL W. LEFFLER, DECEASED, ASSIGNOR TO LEFFLER ELECTRIC SYSTEM, OF CHICAGO, ILLINOIS, A CORPORATION OF MAINE.

COMBINED ELECTRIC RAILWAY AND SIGNAL SYSTEM.

1,131,717.

Specification of Letters Patent.

Patented Mar. 16, 1915.

Application filed August 13, 1908, Serial No. 448,270. Renewed August 10, 1914. Serial No. 856,153.

To all whom it may concern:

Be it known that I, PAUL W. LEFFLER, a citizen of the United States, residing at Chicago, in the county of Cook and State 5 of Illinois, have invented certain new and useful Improvements in Combined Electric Railway and Signal Systems; and I do hereby declare the following to be a full, clear, and exact description of the invention, 10 such as will enable others skilled in the art to which it appertains to make and use the same.

My invention has for its object to provide an efficient combined electric railway and 15 signal system; and to this end, my invention consists of the novel devices and combinations of devices hereinafter described and pointed out in the claims.

The invention is illustrated in the accompanying drawings, wherein like notations refer to like parts throughout the several 20 views.

In said drawings; Figure 1 is a diagram view showing opposite end sections of the 25 line. Fig. 2 is a diagram view showing a section of the line intermediate the opposite end portions of the line illustrated in Fig. 1, said diagram illustrating the parts contained in three block towers, two full track blocks 30 and portions of two others, and the electric connections for the same. Fig. 3 is a view of the lower portion of one of the block towers, partly in elevation and partly in section, with some portions broken away. Fig. 4 is 35 a view of the upper end portions of one of said block towers in elevation. The parts shown in Figs. 3 and 4 go together to make up a complete tower. Fig. 5 is a view of some of the electric devices shown in Fig. 3 40 detached from their housing tower, to-wit, the three solenoids and the circuit connections—contacts which they control. Fig. 6 is a horizontal section on the line $x^6 x^8$ of Fig. 5. Fig. 7 is a horizontal section on the line $x^7 x^5$ of Fig. 5. Fig. 8 is a horizontal section on the line $x^8 x^8$ of Fig. 5. Fig. 9 is a detail 45 of some of the parts shown in Fig. 5, in right side elevation in respect to Fig. 5. Fig. 10 is a view, partly in plan and partly 50 in horizontal section, looking down at the top of one of the block towers. Fig. 11 is a vertical section through the upper portion of one of the block towers, on the line $x^{11} x^{11}$ of Fig. 10. Fig. 12 is a right hand elevation

of the parts shown in Figs. 10 and 11. Fig. 55 13 is a cross section on the line $x^{13} x^{13}$ of Figs. 11 and 12; and Fig. 14 is a view representing the car body in side elevation, and the car trucks and road-bed in vertical longitudinal section, with some parts broken 60 away. Figs. 15 to 18 inclusive are diagram views illustrating abutting sections of the roadway and track magnets and the wiring of the same from the feeding side of the supply circuit. These views abut in the order in which they are numbered reading 65 from left to right.

The signal system, herein disclosed, was designed to supplement the electric railway system disclosed in my companion application, 448,269, executed and filed of even date herewith. The electric devices are supplied from a common source over a common main circuit which extends along the entire line of travel, and the shunting connections, which 70 render the electric devices active for the 75 propulsion of the car and the setting of the signals, are subject to the control of the car. A close combination, therefore, exists between the peculiar electric railway system, 80 disclosed in my said companion application, and the electric signal system herein disclosed and claimed. For the purposes of this case, however, it has not been deemed necessary to detail all of the parts of the 85 electric railway system disclosed in my said companion case; but, on the contrary, only such parts of the railway system have been illustrated as deemed essential to make clear 90 the interdependence of coöperating parts 95 of the two systems. So far as practicable, the illustrated parts common to both cases will be marked with the same reference notations. From the broad point of view, the railway system herein disclosed is within 95 the principles of my foundation prior U. S. Patents 514,718 and 514,561, both of date February 13, 1894, and some of the features disclosed or referred to are covered by my prior Patents 561,898 of date June 9, 1896, 100 and 573,822 and 573,823, both of date December 22, 1896.

In the diagram views, Figs. 1 and 2 and in Fig. 14, a^2 represents the car track rails and a^3 the sectional third rail or conductor. The said sectional third rail is insulated from the ground and its sections are insulated from each other. The car track is divided 105

off into blocks of suitable length, say of one mile, more or less, and the rails a^2 at the ends of the blocks are insulated from each other. At the ends of these track blocks are located block towers a^5 (see Figs. 3 and 4). In these towers are located automatic rheostats for properly directing the current of the main supply circuit and other electric devices which operate under the control of the car to affect the signals, as will later more fully appear.

From a soft iron base bar b , resting on and secured to the ties a^1 , rise the cores or pole pieces of the field magnets. These pole pieces are wound by turns of wires b^2 and b^3 , which coöperate with said pole pieces to form the magnets of the field. These field magnets extend along the entire railway, on the median line of the roadbed, suitably spaced apart from each other and when connected into the supply circuit, hereinafter noted, coöperate with the non-rotating armature and the pole changer carried on the car, as hereinafter noted, to propel the said car along the track.

In Figs. 1 and 2 of the drawings, the windings are not distinguished from the pole pieces, but the magnets made up of said parts are marked with the reference b^1 . The windings of the said magnets are so applied that adjacent magnets will have opposite polarity. The further peculiarity of said windings can be best understood after noting the main parts of the supply circuit.

The dynamo c , shown in Fig. 1, is a D. C. series wound dynamo adapted to deliver a predetermined constant current (preferably of about 75 amperes) and is of the kind which is regulated automatically to vary the voltage as required to meet the load.

For example, said dynamo may be of the kind and regulated in the same way as the dynamos which were formerly used for arc lights in the old Brush system. Of course, it will be understood that, instead of a single such dynamo, several might be employed and be coupled up together in series. The outleading or feeding branch of said supply circuit from said dynamo is composed of a single conductor marked c^1 . The return branch of said dynamo or supply circuit is composed of two conductors c^2 which are connected together at opposite ends of the line by suitable resistance coils, marked, respectively, r and r^1 (see Fig. 1). This form of double return conductor permits the signal lamps to be connected in between the two in multiple, as will later appear. A pair of switches marked, respectively s^1 and s^2 , are located in the supply circuit at the power house, with the former so arranged that it will cut out the supply from the dynamo, and the latter so arranged as to cut out the resistance r between the two conductors of the return branch of the circuit,

thereby enabling the lights of the signal lamps to be cut out without cutting out the other electrical devices supplied from the dynamo.

The outgoing or feeding conductor c^1 , of the supply circuit, is made up of sections which are mechanically separated at the rheostats, in the block towers, but are electrically connected by the contacts and resistance coils of said rheostats; so that these rheostats, at the block towers a^5 , may be said to divide the feeding branch of the supply circuit into sections which correspond to the track blocks. Having further regard to said rheostats, each section c^1 of the supply conductor, which enters a given tower, ends in a long terminal contact c^4 at the rheostat; and that section of said supply conductor c^1 , which leads from the tower, has located therein, at said rheostat, a series of resistance coils and contacts marked with the common reference c^5 , all in series with each other, and more or less of which are adapted to be connected with the terminal contact c^4 , according to the position of a movable bridging contact c^6 which is carried by and insulated from the core of a solenoid d , suitably supported within said tower. Normally, the core of the solenoid d is in its lowermost position, and, when so located, only enough of the coils c^5 will be connected into the supply circuit to afford a minimum resistance; and the normal path for the current, on the supply circuit, from said dynamo is through the said rheostats with minimum resistance; or, otherwise stated, the supply circuit is normally closed through the rheostats; and the current has no other path until a car comes onto a track block, whereupon a new or easier path is afforded, as will presently appear.

Returning now to the magnetic field or track magnets extending along the line of the car's travel it should be noted that the cores or pole pieces of said track magnets b^1 are wound by two separate wires marked respectively b^2 and b^3 and which connect with the supply circuit and best shown in Figs. 15 to 18 inclusive. These four views abut in the order in which they are numbered reading from left to right and may be assumed to show that portion of the roadway including 30 of the track magnets b^1 starting with the third from the right as illustrated in Fig. 2 and counting toward the left. Let it also be noted that Figs. 16 and 17 illustrate a portion of the roadway over which the car is traveling as illustrated in Fig. 2, but in these diagram views Figs. 16 and 17 only the car brushes e^2 are shown. The positions of these brushes serve to indicate the position of the car in respect to that portion of the roadway. The arrows in the wires b^2 and b^3 as shown in Figs. 16, 17 and 18, indicate the track magnets which are

energized and also the assumed direction of the current's travel. Otherwise stated, it will be seen that there are 18 of the track magnets energized or closed into the supply circuit. In tracing the way in which the respective wires b^2 and b^3 are applied to the track magnets it is best to trace in the direction of the arrows. By referring to these views, Figs. 15 to 18, it will be seen that the wire b^2 taps the feed conductor c^1 of the supply circuit, and is then coiled or wound about the pole pieces b^1 of twelve field magnets, and then is connected to a section of the insulated third rail a^3 ; and it will also be seen that the coils of said wire b^2 , about the pole pieces of said successive field magnets b^1 are right and left, or in opposite directions so as to make the polarities of the adjacent field magnets opposite. The same statement applies to the wire b^3 ; but it must be observed that the connections of these two wires b^2 and b^3 to the feed conductor c^1 of the supply circuit and to the sectional third rail a^3 are at different points, lengthwise of the roadway, and, as shown, these points are separated from each other by six field magnets. Otherwise stated, said connections of the field magnet windings or wires b^2 and b^3 , out of which said windings are formed, are staggered, lengthwise of the roadway, in such a manner that both of said wires are closed into the supply circuit simultaneously on the cores of six magnets and separately each on six more magnets; and hence, it follows, that six magnets under the car will be fully energized and two sets more of six magnets each will be half energized, to-wit, one set thereof forward and the other rearward of the fully energized set of six magnets.

From the foregoing, it will be seen that the field or track magnets b^1 are always connected with the feeding conductor c^1 of the supply circuit, but that no current can pass through said field magnets until a car comes on to the block, for the reason that the field circuit is kept open by the insulated sections of the insulated third rail a^3 . When a car comes on to the block, it forms a bridging connection between said third rail a^3 and one of the track rails a^2 , as will presently more fully appear; and, when this occurs, the eighteen field magnets under and adjacent to the car will be connected with the supply circuit. The magnetic field extending along the line of track is, therefore, made up of short sections including only eighteen field magnets each; and it is only one of these field sections on any track block which is closed into the supply circuit at any one time. It will be understood, therefore, that there are several field sections in each track block. Nevertheless, the rheostats at the block towers, in coöperation with the car, control the connecting into the supply cir-

cuit of the successive field sections, which come under the traveling car, as will now be noted.

A wire d^4 connects the outer member of the track rails a^2 with the magnet of the rheostat controlling the largest solenoid d , in each tower; and from the magnet of said solenoid d extends a series of leads d^2 to corresponding contacts, which leads and contacts are both marked with the common reference letter d^2 . Said parts d^2 coöperate with a bridging contact d^3 carried by and insulated from the core of said solenoid to connect the proper member of said parts d^2 with a terminal contact d^4 at the rheostat end of a wire h which leads out from that tower and passes thence along the roadway to the magnet of a solenoid h^2 , which is one of a pair of solenoids controlling the signal lamps and semaphores in the next adjacent tower toward the left, as shown in Fig. 2. From the magnet of the solenoid h^2 , a wire h^1 leads back to a junction with the wire c^1 which leads from the resistance coils and contacts c^5 of the rheostat at that tower, and h^1 is one of the sections of the feeding conductor of the supply circuit, as hitherto noted. These wire sections h and h^1 correspond to the wire d^5 shown in my companion case, but instead of leading directly back from each tower to the feeding conductor of the supply circuit, as in said other case, they take the current forward to the next tower to supply the signal solenoid h^2 therein, and then lead back to a junction with said supply conductor.

The magnet of the main solenoid d is wound with coils of different cross section, and the leads d^2 from these different coils have a corresponding cross section, thus affording paths of varying capacity as required to take care of the varying current which passes over this main shunt circuit and through the magnet of the main solenoid d . The winding of the signal solenoid h^2 is of the proper size to take care of the maximum current which passes over this solenoid circuit. When the bridging contact d^3 is in its lowermost or normal position, as shown in the rheostat at the right in Fig. 2, the lead d^2 of the smallest cross section will be connected into the solenoid circuit; and as the bridging contact d^3 is raised, one step after the other, leads d^2 of greater cross section will be successively connected into the solenoid circuit until the limit is reached with said bridging contact in its highest position, as in the central rheostat shown in Fig. 2; and, when said parts are in this position, all the conductors of the solenoid circuit will be of sufficient cross section to carry, and will, in fact, carry substantially the whole of the current from the supply circuit, as will later more fully appear.

The reasons for winding the solenoid magnet d with coils of different cross sections and for having the corresponding wires and contacts b^2 of corresponding variation in capacity are to avoid the shock to the system which would be occasioned, if the said magnet was wound with a single coil composed of wire of large enough cross section to carry the maximum current, and also to avoid the danger to human life which might result from the accidental bridging across the main track and the sectional third rail. By having the arrangement disclosed, the shunt is gradual.

The car body e is provided with a non-rotary armature f and a suitable pole changer p , as shown in Fig. 14, and which pole changer is subject to the underlying track or field magnets b^1 and operates to commutate the current through the magnets of the armature so as to change the polarity thereof, according to the speed of the car. The track or field magnets b^1 will, therefore, co-operate with the non-rotary armature f on the car to propel the car along the track. Said car has three brushes e^2 ; and two of these, to-wit, the central and one of the end brushes, travel in contact with the sectional third rail a^3 . For the purposes of this case, the electric devices on the car, and the supply connections for the same, might be identical with those disclosed in my foundation Patents 514,718 and 514,561 of date February 13th, 1894. If the electric car shown in this case be assumed to be equipped with the electric devices disclosed in my said prior patents, then the system as a whole would be operative, for the propulsion of the car; but inasmuch as the signal system, herein disclosed, is intended for use with the system for propelling cars, disclosed in my said companion application, the supply both for the track magnets, making up the magnetic field extending along the line of travel, and for the electric devices on the car are assumed to be from a common source, to-wit, the dynamo c of the kind described and to be delivered over the common supply circuit extending along the line of travel and including the sectional third rail and the car as part of the connections, both for the field and the electric devices carried by the car.

Bearing the foregoing statements in mind, and referring back to the diagram views, it can be seen that whenever a car comes on to a given block of the car track, its brushes and trucks will form a bridging connection from the sectional third rail a^3 to the track rails a^2 ; and, hence, that the current from the main feed conductor c^1 of the supply circuit can then pass over the wires b^2 and b^3 , and magnets b^1 to the sections of the third rail on which the brushes are running, and pass thence over the car trucks to one of the track rails which, as shown is the

outer rail; and further, that the current can pass thence over the circuit connections for the solenoids d and h^2 and back to a junction with the feed conductor c^1 of the main supply circuit. Hence, as soon as the car closes the field circuit, a small portion of the supply current can pass over the said solenoid circuit connections or shunt, even while the bridging contacts c^6 and d^3 remain in their lowermost position, as shown in the rheostat at the right in Fig. 2, for the reason that only the minimum resistance is in the normal path of the current at the rheostat. It, therefore, follows that the magnet of the solenoid d in the rheostat controlling the field magnets of a given block will be energized instantly as soon as the car comes on to that block; and, hence, that the core of the said solenoid d will be raised to its limit and carry with it the bridging contacts c^6 and d^3 so as to bring these parts into the position shown in the central rheostat illustrated in Fig. 2, and as soon as this occurs, it is obvious that the bridging contact c^6 will bring into the feeding side of the supply circuit a maximum resistance or number of coils c^5 at the rheostat, and that the bridging contact d^3 will be in position to co-operate with the leads d^2 of greatest cross section. The said maximum resistance which is connected into the feeding side of the supply circuit, at the rheostat, when the bridging contacts thereof are in their uppermost position, is greater than the resistance afforded by the connected-in section of the track field, the car armature magnets and the pole changer on the car, and, hence, as soon as this maximum resistance is connected into the supply circuit at the rheostat of a given block, the current of the supply circuit will take the easier path through the track or field magnets b^1 to the sectional third rail a^3 , and thence through the pole changer p and non-rotating armature f of the car, and back to the outer member of the track rails a^2 , and thence will pass over the shunt circuit connections therefrom through the solenoid d of one rheostat and the solenoid h^2 of an adjacent rheostat, and therefrom back to a junction with the conductor c^1 of the supply circuit on the opposite side of that rheostat. The said shunting circuit connections through the solenoid d of a given rheostat, and the solenoid h^2 of an adjacent rheostat, therefore, become part of the working path of the supply current, when the car is on the track block controlled by that rheostat.

With the system organized as illustrated, the car is assumed to be moving toward the right, and the car track block controlled by a given tower is at the right of said tower; and, hence, the car shown in Fig. 2 is controlling, primarily, the electric devices in the adjacent tower at the left of the car; but, as it will presently appear, however, the car

is also controlling certain signal devices in two other towers. The main current which is taken off from the field circuit by the car brushes, passes through the pole changer p and the windings of the car armature f before it passes to the car track and thence over the solenoid shunt connections.

From the foregoing, the electric system for propelling the car should be sufficiently distinct for the purposes of this case. The signal system dependent on and supplemental to said car propulsion system will next be described.

The signal system.—Suitably supported, at each block tower, are a pair of signal controlling solenoids marked, respectively, h^2 and h^3 ; a pair of semaphore levers marked, respectively, h^4 and h^4 ; and two sets of incandescent lamps marked, respectively, n^1 and n^2 . The core of the solenoid h^2 is connected by red h^5 with the semaphore lever h^4 ; and the core of the solenoid h^3 is connected by red h^6 with the other semaphore lever h^4 . The core of said solenoid h^2 has, at its lower end, a depending bar h^5 of insulating material; and the core of the solenoid h^3 has at its lower end a depending bar h^6 of insulating material.

The sets of lamps n^1 and n^2 are connected in multiple, as hitherto noted, between the two conductors c^2 of the return branch of the supply circuit from the dynamo. For this purpose, a wire n cross-connects the said two wires c^2 of the return branch of said supply circuit; into this loop the upper set of lamps n^1 are directly connected and the lower set of lamps n^2 are indirectly connected by a supplemental wire n^3 tapping the wire n between the solenoid h^2 and a switch n^4 located in said lamp circuit. The lamp circuit wires n and n^3 are both sectioned, on the lamp side of the switch n^4 ; and the bars of insulating material h^5 and h^6 depending from the cores of the solenoids h^2 and h^3 carry, at their lower ends, sliding contacts marked, respectively, n^5 and n^6 which co-operate, respectively, with spring contacts n^7 and n^8 forming the terminals of said sectioned wires, to connect the proper sections thereof, at the proper time, under the action of said solenoids h^2 and h^3 as controlled by the car. Normally, the pairs of spring contacts n^7 and n^8 are separated by the insulating bars h^5 and h^6 , so that both branches of the lamp circuit will be open; or, otherwise stated, the parts will stand as shown in the tower illustrated in Fig. 1. Said solenoid h^2 is in the main shunt from the supply circuit, as hitherto noted when tracing the connections through the rheostats controlled by the car. The other solenoid h^3 , at each tower, is also located in a shunt from said main supply circuit. For this purpose, a wire h leads from one of the car track rails a^2 to the magnet of the sole-

noid h^2 , and from this a wire h^1 leads back to a junction with the wire h leading out from that tower and on to the next solenoid h^3 and being part of the main shunt hitherto noted. For distinction, the shunt over the wires h and h^1 may be called a minor shunt. Bearing these relations in mind, the actions of the solenoids h^2 and h^3 on the signal devices, under the control of the car, can be readily understood. The lamps and their bull's-eye lenses are marked with the same reference letters. Each set of lamps have two of these lenses; to-wit, one colored red and the other colored green facing in opposite directions. In the diagrams, the red lenses are indicated by vertical shade lines and the green lenses by oblique shade lines. The upper set of lamps have their red lenses to the left and their green lenses to the right; and in the lower set, a reverse relation is maintained. The lamps are thus adapted to either direction of the car's travel.

The main shunt wire d^1 and the minor shunt wire h connect to opposite ends of the track block rail. Hence, as soon as a car comes onto a block, a portion of the current which comes on to the car will be shunted over said two different shunt circuits. The effect of this will be that part of the current which goes over the wire h , or the one in advance of the car as shown in Fig. 2, will pass first through the magnet of the solenoid h^2 of the tower in advance of the car, as there shown, and thence come back over the wires h^1 and h to the magnet of the solenoid h^3 of the central tower or one which is controlling the field sections of the block occupied by the car; while, at the same time, the current which is taken off over the main shunt from the block occupied by the car, through the wire d^1 to the magnet of the main solenoid d , and the contacts d^2 , d^3 and d^4 , will go out of that tower, on the wire h which leads to the solenoid h^2 of the next tower to the left; and, hence, the solenoid h^2 at the central and the next adjacent tower to the left will be holding their cores in their uppermost positions; and the magnet of the solenoid h^3 in the tower at the right will be holding its core in its uppermost position. The magnets of the other two solenoids h^2 will be without current, and, hence, their cores will be in their lowermost positions. It, therefore, follows that the solenoids h^2 at the central tower, and the solenoid h^3 at the next tower to the left will be holding their contacts n^5 in position to close the lamp circuit through the upper set of lamps n^1 and in position to hold the semaphore lever h^4 , at each of said towers, in its uppermost position. These towers are both behind the car, and will thus be showing the danger signals to any car approaching from that direction. The solenoid h^2 , in advance of the car, will be holding its core

in its uppermost position, thereby holding up the semaphore lever h^4 at that tower, and holding the contacts n^6 attached to its bar k^6 in position to close the lamp circuit through the lower set of lamps n^2 . These 5 are the clear way signals for the next block in advance of the car. If, however, it had happened that there was another car on this advance block, the current passing over the 10 minor shunt k for that block to the next tower in advance would be coming back over the wire h to the solenoid h^2 of the right hand tower shown in Fig. 2, thereby causing 15 the said solenoid h^2 to lift the semaphore lever h^4 to its uppermost position and to bring the contact n^5 , carried by its core, in position to close the lamp circuit through the upper set of lamps n^1 . Otherwise stated, the danger signals would also 20 be facing the car, as shown in Fig. 2. The design is, therefore, such that there should always be at least two blocks between any consecutive pair of traveling cars, and unless the motorneer meets only the go ahead 25 signals, he knows that there is danger ahead. Otherwise stated, the signal system is of such design as to insure safety signal lights both in advance and in the rear of the car, on any block, in either direction of travel, 30 and to insure danger signals against an approaching car in either direction, for a distance of two blocks ahead and one block behind any given car. It also follows from the nature of the electric connections de- 35 scribed, that no current is available to the track magnets within the insulated track block directly behind the car; and hence, even if the signals of danger should be ignored, no power would be available to the 40 approaching car from the rear. There is thus a double factor of safety provided against rear-end collision, which is the chief one to guard against in a double track system. As soon as a car passes off of a given 45 track block, both shunts from that block will be cut out, and, hence, the solenoids h^2 and h^4 in the third tower behind the car, going in the direction shown in Fig. 2, will both be without current, and all the parts 50 controlled thereby will stand in the position shown in Fig. 1.

Short circuiting devices are provided at each block tower, for preventing the current supplied over the shunt circuit connections, 55 under the control of the car, from passing through any of the solenoids at the said tower. These devices include a pair of hand switches s^3 and s^4 , a short wire s^5 and suitable contacts for coöperation with the said 60 switches in their two different positions. When the said switches s^3 and s^4 are in the position shown in the diagram views Figs. 1 and 2, the solenoids at the towers will be connected in to the shunt circuits provided 65 for the same, under the control of the car.

If, however, the said switches s^3 and s^4 are turned down into their opposite extreme positions, all the shunt connections will be short-circuited so as to keep the current from going through any of the solenoids at 70 that tower. Considering first the switch s^3 , when this is turned down, to its lowermost position, the current supplied over wire d^1 and which would otherwise go on to the solenoid d will pass directly to the wire h 75 at the switch and on to the next left hand tower; and the current which came over this wire h from the right hand tower will pass over the short circuiting wire s^5 at the central tower to the supply conductor c^1 of the main circuit to the left of said tower. 80

Considering the switch s^4 , if this is in its lowermost position, the current which would come in from the section of the supply conductor c^1 at the right, will go directly out over the wire s^5 and on to the next left hand section c^1 of said supply conductor; and the current which would come in over the shunt wire h will pass directly out to the wire h which leads on to the next left hand tower. The switch n^4 in the lamp circuit at each 85 tower has already been noted, and its action is so obvious that it needs no explanation. These switches at the towers are desirable for the purposes of inspection and repair. 90

From the foregoing detailed description, it is obvious that, in this system, there is employed a substantially constant current but a variable voltage according to the load; that the connections for controlling the signals, and the connections for controlling the supply to the track magnets, for propelling the car, both depend upon the automatic rheostats at the block towers. If it were not for the limited amount of resistance normally in the supply circuit at the tower rheostat, no current whatever would be shunted when the car comes onto a given block; and, of course, it would follow that there would be no power available to propel the car and no power available to set the signals. To this extent, the signal and propelling systems herein disclosed are dependent upon each other. 105

From the detailed description, it is obvious, that the shunt circuit connections for both the major and the minor shunts are normally open between the sectional rail and the car track rails. The car and its brushes do the bridging so as to close the shunt 110 circuits at the times when required for the purposes stated. It takes the car and the automatic rheostats, therefore, to control both the propelling and the signal systems. 115

The signal system has so far been described chiefly with reference to the showing thereof made in the diagram views, although all the parts noted will be found illustrated in more or less of the other views. The views numbered 5 to 13, inclusive, illustrate 120

130

the structure of the block towers, the signal devices supported thereby, and the structure of the supports for the electric controlling devices which are housed within the enlarged lower portions of said tower. These structures are so clear from the drawings themselves, that any extended explanation of details is not deemed necessary. It may be serviceable, however, to briefly note a few features.

By reference to Figs. 10, 11 and 12, it will be seen that the lamps and their bull's-eye lenses are mounted within housings a^6 adapted to sleeve over the upper end of the tower mast and thereby be removably secured thereto; and this housing a^6 has itself a removable cap a^7 affording access to the lamps from the top of the tower without the removal of the housing. The part of the tower mast which supports the pivot shafts of the semaphores k^4 and k^4 is provided with removable closures a^8 affording access to the said shafts on the interior of the tower, as shown in Figs. 11, 12 and 13. These closures a^8 bulge outward to afford clearance for the inside crank arms of the semaphores to which the rods k^3 and k^6 are connected. The enlarged lower portion of each tower is also provided with a large opening a^9 (as shown in Fig. 3) covered by a removable closure, to afford access to the solenoid magnets and the rheostat devices inclosed within said part of the tower as a housing. The three solenoids d , k^2 and k^2 , at each tower, are supported by a common skeleton frame q shown detached in Fig. 5; and which frame q is adapted to fit within the enlarged part of the tower a^5 and be rigidly secured thereto in any suitable way. The part of said frame q which supports the large solenoid d is of such construction that it supports the separated resistance coil contacts c^5 which coöperate with the bridging contact c^6 at the rheostat, as shown in the diagrams. The resistance coils c^5 are also shown in Fig. 3. Said frame q also supports the separated contacts d^2 which coöperate with the leads d^2 from the magnet of the solenoid d and the bridging contact d^3 , as shown in the diagram views. The said frame is also of such construction that it will properly guide the said bridging contacts c^6 and d^2 and the insulating bar or rod depending from the core of said solenoid and carrying the said bridging contacts at its lower end.

In Figs. 5 and 8, the contacting surfaces of the bridging contacts c^6 and d^2 are shown as in the form of brushes yieldingly supported by spring holders marked with the same reference letters as the contacts.

By reference to Figs. 5 and 9, it will be seen that the spring contacts n^7 and n^8 forming terminals of the lamp circuit wires n^6 and n^8 are supported in such a way as to be

insulated from each other and from their supports.

It must be understood that the invention herein disclosed and claimed may be embodied in manifold forms of construction; and, hence, that the details illustrated may be widely varied without departing from the spirit of my invention.

What I claim is:—

1. The combination with a car and a track for the same, of electrically operated signaling devices spaced apart from each other along the line of the car's travel, a dynamo of the type and construction which delivers a substantially constant predetermined current but variable in voltage according to load, a circuit from said dynamo into which the said signaling devices are connected in shunt by said car and automatic rheostats in said circuit controlled by the car, said signaling devices being connected around said rheostats, substantially as described.

2. The combination with a track and a car, of block towers spaced apart from each other along said track, a metallic supply circuit, a dynamo of the type and construction which delivers a substantially constant current but variable in voltage according to load, said dynamo being connected to said supply circuit, signaling devices at the towers located in normally opened shunts from said supply circuit, and automatic rheostats in said supply circuit at the said towers, controlled by said car and regulating the current delivered to said signaling devices.

3. The combination with a track and a car, of block towers spaced apart from each other along said track, a metallic supply circuit, a dynamo supplying current to said circuit and which dynamo is of the type and construction which delivers a substantially constant current but variable in voltage according to load, electric signal devices at said towers located in normally opened shunts from said supply circuit, at least one of said shunts including electrical connections between signaling devices at two consecutive towers and another shunt including a signaling device at another tower, and automatic rheostats in said supply circuit at the towers, controlled by said car, and themselves regulating the current delivered to the shunts for the three interconnected signal devices, substantially as described.

4. The combination with a car, of a track for the same, at least one rail of which is divided into blocks insulated from each other, a sectional third rail having its sections insulated from each other and from the ground, signaling towers, one for each of said track blocks, a metallic supply circuit, a dynamo supplying current to the said circuit and which dynamo is of the type and construction which delivers a substantially constant current but variable in voltage accord-

ing to load, electrical signal devices at said towers, located in normally open shunts from said supply circuit and including as elements thereof, sections of said sectional 5 third rail and track rail, and automatic rheostats in the said supply circuit, one at each of said towers, normally connected to close the supply circuit at the said rheostat, but operating under the control of the car to 10 regulate the amount of current delivered to said shunt circuit connections and thereby operate the said signal devices, substantially as described.

5. The combination with a car, of a track 15 for the same, at least one rail of which is divided into blocks insulated from each other, a sectional third rail having its sections insulated from each other and from the ground, signal towers, one at each of said 20 track blocks, a metallic supply circuit, a dynamo supplying current to said circuit and which dynamo is of the type and construction which delivers a substantially constant current but variable in voltage according to 25 load, electric signal devices at said towers lo-

cated in normally opened shunts from said supply circuit and including as elements thereof, sections of said sectional third rail and of the said sectional track rail, at least one of said shunts including electrical connections between signaling devices at two consecutive towers and another shunt including a signaling device at another tower, and automatic rheostats in said supply circuit, one at each tower, normally closing the supply circuit at the corresponding rheostats and operating under the control of the car, to regulate the amount of current delivered to said shunt circuit connections and thereby operating said signal devices and indicating the condition of the particular block section in which there is a car, substantially as described.

In testimony whereof I affix my signature in presence of two witnesses.

PAUL W. LEFFLER.
